E. M. Marshall
ATTORNEY

UNITED STATES PATENT OFFICE.

JOHN EDWARD OGDEN, OF CORNWALL, NEW YORK.

CONCRETE INSERT.

Application filed July 5, 1919. Serial No. 308,687.

To all whom it may concern:

Be it known that I, JOHN EDWARD OGDEN, a citizen of the United States of America, and a resident of Mountainville, town of 5 Cornwall, Orange County, and State of New York, have invented certain new and useful Improvements in Concrete Inserts, of which the following is a specification, reference being had to the accompanying drawings, 10 forming a part thereof.

This invention relates to new and useful improvements in concrete inserts, and its object is to provide a simple and inexpensive device which may be easily embedded 15 in concrete structures during their formation, which is adapted to receive the head or nut of a bolt, and to provide for adjustment of the position of the bolt.

These and other objects of the invention 20 will appear in the following specification in which I will describe the invention, the novel features of which will be set forth in appended claims.

Referring to the drawings:

25 Figure 1 is a sectional elevation of a device of cast metal which is made according to and embodies this invention. This is shown in the condition in which it comes from the casting mold.

30 Figure 2 is a similar section of the same device embedded in concrete showing the positions which its parts assume when a bolt is being inserted.

Figure 3 is another sectional elevation of 35 a device of a somewhat modified form embedded in concrete and with a member secured thereto by a bolt.

Figure 4 is a sectional plan view of the parts shown in Figure 3.

40 Figure 5 is a sectional elevation of a device of still further modified form showing a bolt being inserted therein.

Like characters of reference designate corresponding parts in all the figures.

45 10 designates a body the inner wall of which is cylindrical. This is closed at the top as shown at 11, and is partly closed at the bottom by an inwardly extending annular flange 12 and has ears 13 and 14 projecting from it at spaced intervals. The ears 14 are preferably at the lower end of the body and constructed to form notches 15. 16 is a circular disk provided with a slot 17. This disk is of greater diameter 50 than the opening through the center of the flange 12 and of less diameter than that of

the inside of the body 10. In making the device the disk 16 is preferably put inside of the core 18 which determines the size and shape of the inside of the body. 60

Before specifically describing the structures shown in the other figures of the drawings, I will point out the way in which this device is used. After the body is cast the core 18 is broken up and removed. The disk, 65 however, is too large to come out and therefore remains permanently inside of the body. When a concrete structure is to be made the device is placed on one of the form boards, and if desired, may be positioned thereon 70 by tacks driven through the notches 15. The concrete is poured over and around the device as shown at 20 so that the insert becomes a permanent part of the finished structure.

A bolt 21 may now be inserted by pushing the disk upwardly as shown in Figure 2, until its head or a nut thereon passes the edge of the disk when the latter may fall down on to the flange 12 with the shank of the bolt extending through the slot 17. This 75 slot is narrower than the head or nut of the bolt so that the bolt will be held by the disk. It is to be noted that the slot has sufficient length to provide for the movement of the bolt in it longitudinally. It is also evident 80 that the disk may be rotated on the flange 12 to amplify the range of adjustment of the bolt. When a bolt is in the desired position, a member 22 may be secured by means 85 of it and a nut 23. 90

The ears 13 and 14 strengthen the grasp of the concrete on the device. In Figures 3 and 4 the outer walls of the body 10^a are transversely fluted or ribbed as shown in 24 to increase the grip of the concrete on the 95 body.

The body 10^b in Figure 5 is open at the top. When this form is used it is not necessary to cast the disk 16 in the body as it may be inserted from the top. But in order to prevent the concrete from entering the body, when it is poured, it is necessary to provide a cover 25. Different modifications of structure may be made within the spirit and scope of this invention and I intend no limitations other than those imposed by appended claims. 100 105

What I claim is:

1. The process of forming a concrete insert which comprises embedding a load 110 carrying member within a chamber forming core, casting the body of the insert about

said core and with a flange which will prevent escape of the load carrying member from the insert and then removing the core to leave the load carrying member supported on the flange aforesaid.

2. The process of forming a concrete insert which comprises casting a hollow insert body about a load carrying element and

with a flange to confine the load carrying element within the chamber of the finished insert body.

In witness whereof I hereunto set my hand this 27th day of June, 1919.

JOHN EDWARD OGDEN.

Witness:

I. B. MOORE.
